Atty.

UNITED STATES PATENT OFFICE.

DAVID A. WILKINSON, OF OVERLAND PARK, MISSOURI.

VICE.

1,387,821.

Specification of Letters Patent. Patented Aug. 16, 1921.

Application filed November 29, 1920. Serial No. 426,937.

To all whom it may concern:

Be it known that I, DAVID A. WILKINSON, a citizen of the United States, and resident of the city of Overland Park, county of St. Louis, and State of Missouri, have invented 5 certain new and useful Improvements in Vises, of which the following is a specification, containing a full, clear, and exact description, reference being had to the accompanying drawings, forming a part hereof.

This invention relates to improvements in vises, and has for its primary object a vise provided with a rest so that a number of small articles can be evened up and clamped 15 between the jaws.

A further object is to construct a vise having a guide for evening up small articles to be clamped between the jaws, which guide is removable from the vise when desired.

20 In the drawings—

Figure 1 is a side elevation of my device; Fig. 2 is a front view of the same;

Fig. 3 is a rear view;

Fig. 4 is a top plan view;

25 Fig. 5 is a side elevation of the guide retaining spring; and

Fig. 6 is a side elevation of the rear portion of the screw for operating the jaws.

In the construction of my device, I provide 30 a vise consisting of a movable jaw 7 and a stationary jaw 8. These jaws are pivoted together at the point indicated by the numeral 9. The jaw 8 is provided with a spring 10, the free end of which tends to 35 force the movable jaw outward.

Secured to the stationary jaw is a bolt 11 which has a tongue 12 formed on its head. This is for the purpose of preventing the bolt from turning. The bolt 11 passes 40 through the movable jaw and is provided with a thumb nut 13 by means of which the jaw 7 is operated.

Formed integral with the stationary jaw are projections 14 and 15. The projection 45 15 is provided with a screw-threaded boss 16, through which the screw 17 passes. This is for the purpose of clamping the vise to a table or work bench. The extension 14 is provided with the upwardly-extending flange 18. This forms a recess 19 in which the spring 20 is placed. This spring is higher 50 at its center than at either end and its purpose is to hold the guide in extended or with-

drawn position. The guide is U-shaped and has two prongs, 21 and 22, and the connecting portion 23. This connecting portion is bent at right angles to the prongs 21 and 22, and its central portion is depressed, as indicated by the numeral 24. The purpose of this is to have the portion 24 contact with 60 the spring 20.

Through the rear portion 25 of the flange 18 is inserted a screw 26 which passes above the depressed portion 24 and is screw-seated in the stationary jaw of the vise. This holds 65 the guide in position on the stationary jaw. The jaws of the vise are provided with openings 27. These openings are so arranged that the prongs 21 and 22 will pass through both 70 of the jaws and not hinder the operation thereof.

When it is desired to file a number of small articles, such as latch keys or the like, the guide or gage is pushed forward to assume the position shown in Fig. 1, the pattern and a number of blanks placed thereon, and the jaws tightened. This will insure the leveling up of all of the key blanks.

Each of the jaws is also provided with a horizontal semi-circular recess 28 and a vertical semi-circular recess 29. The purpose of these recesses is to grip the shank of an ordinary door key when filing the same and hold it securely against any twisting tendency. When it is desired to remove the 85 guide, the guide is moved back until it contacts with the rear wall 25 of the flange 18. The screw 26 is then removed and the gage can be withdrawn from the opening and removed from the vise.

The vise can also be used for ordinary work by merely pulling the guide back, as before mentioned. The ends of the prongs 21 and 22 will then be withdrawn into the head of the stationary member of the vise.

Having fully described my invention, what I claim is:

1. A vise comprising a movable jaw and a stationary jaw, a guide slidably mounted in said jaws and extending entirely therethrough, a bolt and a nut mounted thereon for operating the movable jaw, means for holding the guide to the vise, and clamping means carried by the stationary jaw for securing the device to a work bench.

2. A vise comprising a stationary and a

movable jaw, a bolt and a nut mounted thereon for operating the movable jaw, extensions formed integral with the stationary jaw, a flange formed on one of said extensions, said flange forming a recess, a spring located in said recess, a U-shaped guide slidably extending through both members, said U-

shaped guide having its closed portion contacting with the spring in the recess, and a screw extending through said recess for holding the guide in position. 10

In testimony whereof, I have signed my name to this specification.

DAVID A. WILKINSON.
